US0D1038196S

(12) **United States Design Patent** (10) **Patent No.:** **US D1,038,196 S**
(45) **Date of Patent:** **** Aug. 6, 2024**

(54) **CHASSIS**

(71) Applicant: **HAI ROBOTICS CO., LTD.**,
Guangdong (CN)

(72) Inventor: **Jin Jiang**, Guangdong (CN)

(73) Assignee: **HAI ROBOTICS CO., LTD.**,
Shenzhen (CN)

(**) Term: **15 Years**

(21) Appl. No.: **29/834,268**

(22) Filed: **Apr. 11, 2022**

(30) **Foreign Application Priority Data**

Oct. 19, 2021 (CN) 202130685376.1

(51) **LOC (14) Cl.** **15-99**

(52) **U.S. Cl.**

USPC **D15/199**

(58) **Field of Classification Search**

USPC D15/122, 199; D21/578; D34/18, 28, 34

(57) **CLAIM**

The ornamental design for a chassis, as shown and described.

DESCRIPTION

FIG. 1 is a first perspective view of a chassis showing my new design;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings represent portions of the chassis that form no part of the claimed design.

1 Claim, 8 Drawing Sheets
